UNITED STATES PATENT OFFICE

JAMES GODFREY WILSON, OF NEW YORK, N. Y.

FIREPROOF SHUTTER, DOOR, &c.

SPECIFICATION forming part of Letters Patent No. 700,873, dated May 27, 1902.

Application filed February 5, 1902. Serial No. 92,710. (No model.)

To all whom it may concern:

Be it known that I, JAMES GODFREY WILSON, a subject of Edward VII, King of Great Britain, residing at New York, in the county 5 of New York and State of New York, have invented certain new and useful Improvements in Fireproof Shutters, Doors, &c.; and I do hereby declare the following to be a full, clear, and exact description of the invention, such

as will enable others skilled in the art to which it appertains to make and use the same.

My invention relates to certain improvements in and relating to shutters, doors, &c., but particularly relates to doors and shutters 15 that are provided with a metal sheathing.

The object of my improvement is to overcome a serious disadvantage that at present attaches to articles of this sort; and with this end in view my invention consists in certain 20 details of construction and combination of parts, such as will be hereinafter fully set forth and then specifically be designated by the claims.

In the accompanying drawings, which form 25 a part of this application, Figure 1 is a broken isometric perspective of a shutter constructed in accordance with my improvement, and Fig. 2 a vertical section of a portion of such shutter.

30 Similar numbers of reference denote like parts in both figures of the drawings.

The particular style of shutter which I have illustrated is composed of wooden slats or bars hinged together, so as to fit closely and 35 be capable of rolling, while the surfaces of these slats or bars are covered with sheet metal, with preferably a layer of asbestos interposed between the wood and the metal which covers the outer face of said bars.

40 I have ascertained that a shutter or door composed of wooden bars or slats sheathed with metal is not fireproof for the following reason: When such a shutter is subjected to intense heat, the wood will be burned and 45 will become charcoal. As the wood burns gases will be liberated which by their great pressure will puff out and burst the metal sheathing, so that the fireproof quality of the latter is destroyed.

50 I have ascertained by actual test that if a

plurality of holes or openings be made in the metal sheathing on the outside face or faces the intense heat will burn the wood into charcoal, but the gases will escape outwardly through these openings or holes, and thus relieve the metal sheathing from inside pressure, so that a shutter thus perforated will actually be fireproof and will not become distorted by intense heat.

55 Referring to the drawings, 1 represents the wooden bars or slats; 2, the metal sheathing; 3, the asbestos interposed between the wooden bars or slats and the metal sheathing which covers the outside faces of these bars or slats, and 4 the perforations through the sheathings of the various bars or slats. If desired, these perforations may be plugged with any suitable fusible plug 5, as shown in the instance of the lower slat at Fig. 2, although this is a mere matter of choice and has nothing to do with my invention.

60 Of course I do not wish to limit my invention to shutters or doors specifically, since it will be clear that my improvement may be applied in the instance of any supposed fireproof structure which comprises a core or interior of wood and an external metal sheathing, such as metal-covered sliding or folding doors, window-casings, moldings, &c.

65 It will of course be clear that after the interior of the bars or slats is burned into charcoal the latter, being a very poor conductor of heat, will not interfere with the fireproof nature of the structure; also, while the asbestos may be used as above set forth it will 70 be clear that the same might be dispensed with altogether or other suitable material employed as a substitute, and I do not wish to be limited in this respect.

75 Having thus described my invention, what I claim as new, and desire to secure by Letters Patent, is—

1. As an improved article of manufacture, a fireproof structure comprising an inner core or portion of wood and an exterior sheathing 80 of metal having its outer face perforated, substantially as set forth.

2. As an improved article of manufacture, a shutter or door having a core of wood or the like and a sheathing of metal, the face of 85

said metal having a plurality of perforations, substantially as set forth.

3. As an improved article of manufacture, a rolling or flexible shutter formed of wooden slats or bars and sheathings of metal around said slats or bars, said metal sheathings having in their outer faces perforations whereby communication is established between the

outside air and the wooden cores, substantially as set forth. 10

In testimony whereof I affix my signature in presence of two witnesses.

JAMES GODFREY WILSON.
